(57) **CLAIM**

We claim the ornamental design for a camera follow focus substantially, as shown and described.

DESCRIPTION

FIG. 1 is a first perspective view of a camera follow focus in accordance with the present design.

FIG. 2 is a second perspective view of the camera follow focus of FIG. 1.

FIG. 3 is a rear view of the camera follow focus of FIG. 1.
FIG. 4 is a front view of the camera follow focus of FIG. 1.
FIG. 5 is a top plan view of the camera follow focus of FIG. 1.

FIG. 6 is a bottom plan view of the camera follow focus of FIG. 1.

FIG. 7 is a left side view of the camera follow focus of FIG. 1; and,

FIG. 8 is a right side view of the camera follow focus of FIG. 1.

The broken lines depict portions of the camera follow focus in which the design is embodied and form no part of the claimed design.
